UNITED STATES PATENT OFFICE.

EDWARD C. BASSFORD AND BENJAMIN DAWSON, OF SHERIDAN, WYOMING.

LISTING-PLOW.

SPECIFICATION forming part of Letters Patent No. 749,656, dated January 12, 1904.

Application filed March 18, 1903. Serial No. 148,406. (No model.)

To all whom it may concern:

Be it known that we, EDWARD C. BASSFORD and BENJAMIN DAWSON, citizens of the United States, residing at Sheridan, in the county of 5 Sheridan and State of Wyoming, have invented a new and useful Listing-Plow, of which the following is a specification.

This invention relates to listing-plows; and it has for its object to provide a device of this 10 class which shall possess superior advantages in point of simplicity, durability, and general efficiency.

With these ends in view the invention consists in the improved construction, arrangement, and combination of parts, which will be 15 hereinafter fully described, and particularly pointed out in the claims.

In the accompanying drawings, Figure 1 is a longitudinal vertical sectional view. Fig. 20 2 is a rear elevation, partly in section, of the device shown in Fig. 1. Fig. 3 is a bottom plan view of the device.

Corresponding parts in the several figures are indicated by similar numerals of reference.

25 The plow-beam, which is designated 1, is made of iron and is curved downwardly at its rear end, so as to form the standard 2, which merges with the foot-piece 3, which latter is provided with an upwardly and rearwardly extending bifurcated bracket 4, between the members of which the lower ends of the handles 5 are securely bolted, the upper ends of said handles being suitably spaced in the usual manner. The foot-piece 3 is tapered forwardly 30 to a point and is provided with laterally-extending wings 6, which, in conjunction with the point of the foot-piece, serve to support the plow-point 7, which is of the ordinary triangular or arrow-head pattern.

40 8 8 designate a pair of spindles which are provided with base-plates 9, from which they extend laterally in a forward direction, as shown most clearly in Fig. 3 of the drawings. The base-plates are clamped by means of bolts 45 10 10 upon the standard 2 at a suitable point above the foot-piece, the point of adjustment of said spindle-carrying plates being easily regulated by simply loosening the nuts upon the bolts 10 and reseating them after bringing 50 the base-plates to the desired position. The

spindles 8 carry the disks 11, which are provided with hubs or caps 12, in which antifriction-balls 13 are preferably placed for the purpose of reducing friction to a minimum. The front edges of the disks 11 converge directly 55 in rear of the arrow-point 7, as will be readily seen in Fig. 2 of the drawings.

14 designates a curved shield which is provided with a slot 15, whereby it may be adjusted upon the standard 2 above the disk-carrying spindles, the said shield being provided with L-shaped attaching-plates 16, perforated for the passage of a bolt 17, whereby the said shield may be placed in position with its edges engaging the rear sides of the disks 60 11. This shield serves to keep the rear sides of the disks free from dirt. It also serves to brace the said disks and to steady their movement accordingly, and it consequently adds to 65 the efficiency of the device.

70 The operation of this invention will be readily understood from the foregoing description, taken in connection with the drawings hereto annexed, by those skilled in the art to which it appertains. The point of the plow will 75 open the furrow, and the disks will thus be relieved of a large portion of the strain to which disk implements are usually subjected, the sole function required of said disks being to dispose of the soil at the sides of the furrow. 80

The general construction of the invention is simple and inexpensive, and our improved implement will be found useful and serviceable for the purposes for which it is designed.

85 We desire it to be understood that while we have described a simple and preferred form of our invention we do not limit ourselves to the structural details herein set forth, but reserve the right to any changes, modifications, and alterations within the spirit and scope of our 90 invention and which may be resorted to without sacrificing the utility of the same.

Having thus described the invention, we claim—

1. In a listing-plow, a plow-beam having a 95 downturned standard merging with a foot-piece carrying a point, in combination with spindle-carrying plates clamped upon said standard, and rotary disks mounted upon the spindles.

2. In a listing-plow, a plow-beam having a downturned standard merging with a foot-piece having a point provided with laterally-extending wings, a plow-point mounted upon 5 said point and wings, spindle-carrying plates clamped upon the standard, and disks mounted upon the spindles and converging forwardly to coöperate with the plow-point.
3. In a device of the class described, a beam 10 having a downturned standard merging with a foot-piece, spindle-carrying plates clamped adjustably upon said standards, disks mounted upon the spindles and provided with hubs or caps, and antifriction-balls interposed between 15 said caps and spindles.
4. In a listing-plow, a beam having a downturned standard merging with a foot-piece, spindle-carrying plates clamped adjustably upon said standard, a slotted shield engaging said standard and having edges engaging the 20 rear sides of the disks, and means for retaining said shield in position.

In testimony that we claim the foregoing as our own we have hereto affixed our signatures in the presence of two witnesses.

EDWARD C. BASSFORD.
BENJAMIN DAWSON.
